(57) **CLAIM**

The ornamental design for a display screen with graphical user interface, as shown and described.

DESCRIPTION

FIG. 1 is a front elevational view of an embodiment of a display screen with graphical user interface of our new design; and,

FIG. 2 is a front elevational view of a second embodiment thereof.

The broken lines illustrate the display screen and form no part of the claimed design. The broken lines illustrate portions of the graphical user interface and form no part of the claimed design.

1 Claim, 2 Drawing Sheets

FIG. 1

FIG. 2
